UNITED STATES PATENT OFFICE.

ROBERT FARIES, OF PITTSBURGH, PENNSYLVANIA.

RAIL-ANCHOR.

1,392,407.

Specification of Letters Patent.

Patented Oct. 4, 1921.

Application filed December 9, 1919. Serial No. 343,587.

To all whom it may concern:

Be it known that I, ROBERT FARIES, a citizen of the United States, and a resident of Pittsburgh, in the county of Allegheny and State of Pennsylvania, have made a new and useful Improvement in Rail-Anchors, of which the following is a specification.

My invention relates to railway tracks and consists in a device for preventing the longitudinal creeping of the rails over the cross ties.

One object of my invention is to provide an anti-creeping device which does not depend for its efficiency upon accurate assembly with the rail. A further object is to avoid cutting or drilling the rail to apply the anchor. Another object is to provide a positive anchor against substantial movement of the rail in either direction and security in the event of forces alternating in the direction they tend to move the rail.

I prefer that my anchor elements be combined with a tie plate and Figure 1 of the accompanying drawings is a plan of part of a cross tie and rail equipped with my device in that form; Fig. 2 is a vertical section transversely of the rail and taken on line 2-2 of Fig. 1; Fig. 3 is a plan of a modified anchor disassociated from the tie plate; Fig. 4 is an elevation of the anchor shown in Fig. 3; Figs. 5 and 6 are respectively, plan and elevation of another modification.

In the preferred form, a rectangular tie plate 1 is spiked to the cross tie and provided with a shoulder ridge 2 adapted to extend parallel with the rail and engage one side of the rail base. A coöoperating shoulder ridge 3 presents converging surfaces 4 and 5 at horizontal angles to the side of ridge 2 and spaced far enough away from the same to admit the base of a rail between them with a substantial margin between the edge of the rail flange and the nearest point on ridge 3 when ridge 2 contacts with the rail base.

I insert small rollers 6 and 7 between surfaces 4 and 5 respectively and the rail base. The diameter of these rollers is less than the distance between the rail and the outer portion of either surface 4 or 5 but is larger than the distance between the rail and the inner portion of either of the converging surfaces so that the roller members act as wedges between the rail and ridge 3.

A spring member 8 fits around ridge 3 and its ends form spring clips 9 and 10 which

respectively engage rollers 6 and 7 and tend to keep them in contact with the rail base and ridge 3. I protect rollers 6 and 7 and the spring clips 9 and 10 from dirt and rain with a cover plate 11 which also prevents disassembly of the rollers from the other anchor parts.

Any movement of the rail in the direction of arrow A will be resisted by the wedging action of roller 6. Movement in the opposite direction will be resisted by roller 7. I prefer to make the rollers of hard steel and groove or knurl their surfaces so as to cause them to bite into the contacting rail and ridge.

In the modification shown in Figs. 3 and 4, the anchor does not constitute part of the tie plate nor is it necessarily spiked to the tie. The anchor is assembled with the rail base adjacent the side of the tie and initial movement of the rail toward the tie causes the anchor to engage the tie and wedge the rail. The ridges corresponding to ridges 2 and 3 are provided with integral top flanges 12 and 13 respectively which approach each other and engage the top of the rail base. This prevents the anchor from dropping below the rail. The adjacent faces of flanges 12 and 13 are so spaced from each other that the anchor may be canted to be applied to or be removed from the rail or to be slid along the rail to a tie engaging position.

It will be understood that every tie is not provided with an anchor and that in the event of one way traffic over the track only creeping movement in the direction of the traffic need be resisted. In this modification only one inclined surface, 14 and one roller, 15 are provided for each anchor.

Figs. 5 and 6 illustrate a modification in which the anchor resists creeping movement in either direction and is especially adapted for use around slip switches, draw bridges, terminals and other special track installations. This anchor is assembled with the rail similarly to the anchor illustrated in Figs. 3 and 4. Here, however, it is positioned approximately midway between two ties and braced against both of them and in this modification two inclined surfaces and two rollers are used in each anchor.

The advantages of my device are its simplicity, strength and absence of any machine work necessary to put it into service. The rail is not cut or drilled for assembly with the anchor and the latter may be posi-

tioned at any point on the rail either when installed or at any later time when readjustment may be desirable. The wedging or locking operation is simple and the greater 5 the force moving or tending to move the rail, the tighter the rail is gripped by the anchor.

I claim:—

1. In a rail anchor, a vertical, rail engaging ridge, an inclined ridge spaced therefrom, a roller adapted to contact with said inclined ridge and the side of a rail positioned between said ridges, and means for maintaining contact of said roller with said inclined ridge and the rail.
- 10 2. In a rail anchor, a ridge adapted to engage one side of a rail, a ridge spaced therefrom and having a surface inclined toward the first mentioned ridge, rotatable rail wedging members adapted to be inserted be-

tween said ridges and means for yieldingly holding said members in rail wedging position along said inclined surface.

3. In a rail anchor, a base plate, an upstanding flange extending longitudinally thereof and substantially from end to end, a 25 relatively short, upstanding ridge spaced from said flange and provided with vertical surfaces inclined toward said flange, wedging members contacting with said inclined surfaces, and a spring bent around said short 30 ridge with its ends extending inwardly from the ends of said ridge and adapted to push said wedging members along said inclined surfaces.

In testimony whereof, I have hereunto 35 subscribed my name this 28th day of November, 1919.

ROBERT FARIES.
